GAS PISTON FOR OPERATING AUTOMATIC
GUN BREECH LOCKS

Paul H. Dixon, Rockford, Ill., assignor, by mesne
assignments, to the United States of America
as represented by the Secretary of the Army

Application December 16, 1946, Serial No. 716,469

1 Claim. (Cl. 89—193)

1

This invention relates to ordnance and more particularly to gas operated automatic guns of the type commonly referred to as cannons.

It is desirable to reduce to a minimum the weight and vibration of small cannons used in airplanes. Moreover, it is increasingly important to raise the cyclic rate of such cannon in view of the fact that an enemy airplane is usually in the gunners' sights for only a few seconds at a time and during such time as many rounds as possible should be fired. In prior attempts to increase the cyclic rate of cannons it has been found that the harmonics of the moving parts of said cannons is such that not only the accuracy of fire is reduced and the strain on the gunner is increased but also that such undesirable harmonics defeats to a considerable extent the attainment of the increased firing rate and has in some instances made it dangerous to fire said cannons.

After a gun or cannon has been fired the breechblock or bolt of the cannon is commonly retained in a locked position against recoil until pressure in a bore of a barrel of the cannon has dropped below a certain point, it being apparent that premature unlocking and opening of the bolt results in the loss of propellant force applied to the projectile and causes carbon deposits and sometimes explosions in the receiver. Moreover it has been found that when cannon are used in small turrets, blowback gases should be kept at a minimum thereby insuring against such gases polluting the air in the turrets and otherwise interfering with the comfort and safety of the gunners in the turrets. In order to attain a high cyclic rate it is highly desirable that the bolt, after being unlocked, and parts associated with said bolt shall be moved in recoil and counter-recoil as fast as possible and shall be so constructed and mounted for movement that vibration in the gun shall be reduced to a minimum.

It is an object of the present invention to provide a gas operated automatic cannon which will fire at a rate greater than that of cannons now in use and which when fired at such rate is smooth and effective in its operation.

With the above object in view and in accordance with a feature of the present invention, there is provided an automatic cannon comprising a barrel having a bore provided with a cartridge chamber, a bolt and associated parts movable to and from a battery position adjacent to the barrel, means for locking said bolt in battery position and for unlocking said bolt,

2

an expansion chamber, a passage extending from said expansion chamber to a portion of the bore located just forward of said cartridge chamber, and an actuating member which is movable in and forms part of said expansion chamber and which is operatively connected to said locking and unlocking means, the construction of the passage, the expansion chamber, the actuating member and said locking and unlocking means being such that pressure in the expansion chamber caused by gases escaping into it from the bore, after increasing to a point at which it is approximately equal to the pressure in the bore and having actuated said means to unlock said bolt, continues to rise for a substantial period to exert an increasing force against the bolt and parts associated with the bolt to assist blowback action of the case of the fired cartridge of said gun rapidly to move the bolt and parts associated therewith to recoiled positions. When the gun is mounted in small turrets such as above referred to, the unlocking of the bolt is preferably delayed somewhat by reducing the cross sectional area of said passage, the construction and arrangement being such that the unlocking takes place when the residual gas pressure in the bore of the barrel is low or if desirable after said residual pressure has been entirely dissipated.

In order to insure that the bolt shall be moved rapidly in recoil after being unlocked and to reduce the vibration of the gun when it is fired at a high cyclic rate, the illustrative gun is provided with two separate expansion chambers spaced circumferentially of the barrel and members, which are movable in and form parts of said chambers, respectively, acting under increasing pressure in the chambers to unlock the bolt and then to exert increasing force against the bolt.

Another object of the invention is to conduct unburned gases from the barrel of a cannon to one or more expansion chambers, to unlock the bolt through mechanism operated by increasing pressure which is developed in the chambers and is during such time somewhat less than the decreasing pressure in said bore, and thereafter to cause pressure of gas in the chambers to increase to a point in which it is substantially greater than that in the barrel while acting through said mechanism against the unlocked bolt either independently or in cooperation with blowback action of the case of the

fired cartridge against the bolt to cause rapid recoil movement of said bolt.

By providing the illustrative construction the cyclic rate of cannon has been materially increased and said improved cannon when firing at or near its highest cyclic rate has not sufficient vibration to be objectionable.

The various features of the invention will be understood and appreciated from the following detailed description read in connection with the accompanying drawings, in which

Fig. 1 is a side elevation of the illustrative gun, parts of which have been broken away and parts of which are shown in section;

Fig. 2 is an enlarged side view, partly broken away, showing portions of mechanism for unlocking a bolt of the gun;

Figs. 3 and 4 are full-size sections of the gun on lines III—III and IV—IV of Figs. 2 and 3 respectively;

Fig. 5 is an enlarged side view, partly in section, showing a bolt assembly of the gun locked in battery position.

Fig. 6 is a view corresponding to the rear portion of Fig. 5 showing portions of the bolt assembly unlocked, ready for movement in recoil;

Fig. 7 is an exploded view of the bolt assembly; and

Fig. 8 is a chart showing the gas pressure in a bore of the barrel of the gun and in operating chambers which will be described later, at different times after ignition of the cartridge in the gun.

With the exception of gas operated mechanism, which will be hereinafter described in detail, for unlocking a bolt or breechblock 20 (Figs. 1, 2, 5, 6 and 7), the illustrative gun is similar to the well-known Hispano-Suiza 20 mm. gun and comprises a cradle 22 upon which the gun slides to a slight extent in recoil and counter-recoil. The gun comprises a receiver 24 to the forward end of which is screwed a tube or barrel 26, and a recoil spring 28 (Fig. 1) mounted upon the barrel and having its front and rear ends in engagement with front and rear recoil spring seats 30, 32 respectively secured to the barrel and to a recoil housing assembly 33 fixed to a mounting bracket 35 bolted to the cradle 22.

Mounted for forward and rearward sliding movement in the receiver 24 is a breechblock or bolt assembly 34 (Figs. 1, 5 and 7) comprising the bolt 20, which has a longitudinal bore 36 (Fig. 5) for receiving a firing pin 38 (Figs. 5 and 7), a pair of bolt slides 40 (Figs. 1, 2, 5, 6 and 7) which are secured together by a key 42 extending through an elongated slot or recess 44 (Fig. 7) of the bolt 20 and which are slidable lengthwise on supporting faces 46 of the bolt, and a lock 48 a cylindrical forward end of which fits in a transverse groove 50 (Figs. 1, 5 and 6) of the bolt and is constructed and arranged to secure the bolt in battery position. When the gun is in battery position the bolt 20 is held against a chambered cartridge 49, as best shown in Fig. 5, the slides 40 being in the forward positions relatively to the bolt, with the key 42 approximately in engagement with the forward end of the recess 44. When the slides 40 are thus positioned, recesses 52 (Figs. 1, 5, 6 and 7) in the slides 40 will have moved forward with relation to the bolt 20 into positions (Fig. 5) out of register with a rear portion 54 (Figs. 5, 6 and 7) of the lock 48, a rear beveled face 55 of which is then in engagement with a face 57 (Figs. 1, 5 and 6) of an abutment or key 56 secured to the receiver 24.

The slides 40 are constantly urged to their forward positions shown in Fig. 5 upon the supporting faces 46 with relation to the bolt 20, by rods 45 (Figs. 5 and 7), which are surrounded by a slide spring 47, respective ends of each spring being in engagement with a head of its rod 45 and a respective lug 51 extending from each side of the bolt.

It will thus be apparent that before the bolt 20 can be unlocked it is necessary to move the slides 40 into such positions that the rear portions 54 of the lock 48 are in register with and can be moved into the recesses 52 of the slides 40 to permit said lock to be raised out of engagement with the key 56, as shown in Fig. 6.

The barrel 26 is provided with circumferentially spaced gas ports or orifices 58, 58a just in front of a cartridge chamber 59 of a bore 60 of the barrel and are spaced equal distances from 20 a vertical plane 61 through the bore axis of the barrel. (See Fig. 3.) In communication with the ports 58, 58a are ports 62 which are formed in a block 63 secured by tap pins 67 (Fig. 3) to the barrel 26 and which communicate with cylindrical chambers 64 (Figs. 2 and 4) respectively formed in the block. The gas ports 58a which are of a diameter of approximately $\frac{1}{16}$ " and are smaller than the ports 58, 62 are formed in a silver heat dissipating plug 65 (Figs. 2, 3 and 4) fitting in a recess 66 of the barrel. The ports 58, 58a and 62 collectively may be referred to as a gas passage which extends between the bore 60 and one of the chambers 64. The recess 66 may also be described as an enlarged portion of a passage in the gun barrel, the heat dissipating plug 65 fitting in said enlarged portion and having said restricted orifice 58a which forms part of and connects, spaced portions of the gas passage extending from the bore 60 to one of the chambers 64.

Slidable in each of the chambers 64 is a hollow piston or actuating member 68 (Figs. 2, 3 and 4), a head 70 of which is arranged adjacent to an associated slide rod 72 mounted for reciprocation in a guideway 74 (Figs. 2 and 4) of the receiver 24.

Assuming that the gun has just been fired, a projectile 76 of the cartridge moves forward in the bore 60 and passes the gas ports 58, portions 50 of the burning and expanding gases passing through the gas passages formed by said ports 58, 58a and 62 into the chambers 64. Such gases at that time are only partially burned and therefore, as they continue to burn, such gases increase 55 the pressure in the chambers 64 causing the pistons 68 to move rearward. At the time the projectile 76 leaves the barrel, as represented by point 80 on the gas pressure-time after ignition curve on the chart shown in Fig. 8, the gas or 60 powder pressure in the bore 60 of the barrel 26 is slightly greater than the gas or powder pressure in the chambers 64 but at such time the pressure in the bore is dropping rapidly. At the time represented by point 82 (Fig. 8) the increasing 65 pressure in the chambers 64 is equal to the pressure in the bore 60 and thereafter continues to increase, the peak portion of the "gas pressure-time after ignition" curve in the chamber lying outside the superimposed "gas pressure-time after ignition" curve of the bore of the gun barrel. Each of the ports 58a is of suitable size to restrict to a considerable extent the flow of gases from the expansion chamber 64 back into the bore, thereby insuring the availability of an expansible 70 force, after the residual pressure in the bore, 75

which heretofore has been used for the final thrust in moving the bolt assembly back to recoil position, is gone. By providing expansion chambers 64 between the port 58a and the hollow piston 68 an expanding gas volume is provided as distinguished from the prior art construction wherein kinetic energy of the gases from the burning propellant is used.

Immediately after the gun is fired, built up pressure of the gases in the chambers 64 causes the pistons 68 to move rearward slightly with the result that after the pistons have moved approximately $\frac{1}{16}$ " representing an initial clearance between the slide actuating rods 72 and the forward ends of the slides 40, rearward pressure is exerted against said slides. While the projectile 76 is moving along the bore 60 of the barrel 26 the pressure in said bore is very high and the pressure exerted by the case of the fired cartridge against the bolt 20 causes the lock 48 to be forced with very heavy pressure against the abutment 56, said lock being forced by the reaction of the abutment 56 with considerable pressure against the slides 40 with the result that said slides are forced upward with substantial binding pressure against longitudinal guides 83 (Figs. 1 and 2) of the receiver 24. During the time that the projectile 76 is moving along the bore 60 of the barrel 26 pressure in the chambers 64 increases as shown by the "gas pressure-time after ignition" curve of said chambers. At the time of muzzle contact of the projectile 76 the pressure in the barrel bore 60, which pressure reaches a maximum of 50,000 pounds per square inch, will have been reduced to approximately 5,400 pounds per square inch, for example, the pressure in the chambers 64 at that time being high enough to have moved the rods 72 rearwardly approximately $\frac{1}{2}$ inch and the slides 40 approximately $\frac{1}{16}$ inch, the bolt lock 48 at such time being about ready to be forced into the recesses 52 of the slides to its position illustrated in Fig. 6 to permit said lock to be cammed up by the key 56 into the recesses 52 so that the lower surface of the lock can ride rearward over the upper surface of the key along guides (not shown) in the receiver.

When the bolt 20 has been unlocked blowback action of the case of the cartridge in the bore 60 upon said bolt 20 causes recoil movement of the bolt in the receiver 24 against the action of driving and buffer springs 84 and 86 respectively (Fig. 1). Because of the fact that the ports 58a of the heat dissipating plugs 65 are small and the gases which are in the chambers 64 are still burning and cannot readily escape back into the bore 60, such gases continue to increase in pressure in the chambers to attain a pressure of approximately 4,600 pounds per square inch indicated by the peak portion 88 (Fig. 8) of the "gas pressure-time after time ignition" curve of said chambers.

After the slides 40 actuated by the pistons 68 have moved rearward to the proper positions to permit the bolt 20 to be unlocked, the slide moves approximately an additional $\frac{1}{8}$ " against the action of springs 47 until their key 42 engages the rear end of the elongated slot 44 (Fig. 7) continued rearward movement of the slides of approximately $\frac{1}{8}$ " under the action of the pistons 68 imparting momentum in recoil to the bolt 20 and causing, in combination with some blowback action of the case of the fired cartridge against the bolt, the rapid movement of the bolt and its associated parts in recoil. Recoil movement of

the slides 72 is limited by engagement of rear ends of the slides with shoulders 89 (Fig. 2) of the receiver 24, the heads 70 of the pistons 68 at such time being in engagement with surfaces 91 (Fig. 4) of the receiver 24.

When it is desired to delay the unlocking of the bolt 20 until the pressure in the bore 60 of the barrel 26 has been reduced to a minimum or has been entirely dissipated, the cross sectional areas of the gas ports 58a are reduced with the result that a "pressure-time after the ignition" curve taken in the chamber 64 will be somewhat similar to that shown in Fig. 8 but will have a peak which is lower than and is arranged to the right of the peak portion 88. With such construction the bolt 20 will not be unlocked until the residual pressure in the barrel bore 60 is quite low and by the time the case of the cartridge has been withdrawn sufficiently to permit the flow of gases from the spent cartridge into the receiver the pressure in the bore of the barrel will be practically dissipated. As above stated, by further restricting the cross sectional areas of the ports 58a, the unlocking of the bolt 20 may be delayed until the pressure in the bore 60 of the barrel 26 has been entirely dissipated. It has been found that there is sufficient expansive force left in the chambers 64 after the dissipation of the pressure in the bore 60 of the barrel 26 to maintain a high even rate of fire.

As the bolt assembly 34 is moved in recoil the following round is delivered to the receiver 24 and as said assembly moves forward in counter-recoil under the action of buffer springs 84, 86 the cartridge is chambered. After forward movement of the bolt 20 has been arrested, the slides 40 under their forward inertia and the action of the springs 47 move forward with relation to the bolt 20 until the slide key 42 engages the forward end of the slot 44 in the bolt. In order to insure against the bolt 20 and the slides 40 bounding back out of battery position after their cartridge chambering movement is checked, inertia blocks 90 (Figs. 1, 2 and 5) are mounted in the slides. During forward movement of slides 40 upon the bolt 20 the lock 48 is cammed down by the slides 40 into engagement with the key 56 to lock the bolt assembly 34 against rearward movement. The firing pin 38 which is cocked during its recoil movement with the bolt 20 is then released to fire the gun to start the operation of another cycle such as above described.

Having described my invention, what I claim as new and desire to secure by Letters Patent of the United States is:

In an automatic rapid fire gun having a barrel including a cartridge chamber in the rear portion of its bore, a longitudinally reciprocable breechbolt closing the rear end of said chamber when said breechbolt is in forward position, means releasably locking said breechbolt in forward position, means forming a gas cylinder in fixed parallel radially-offset relation with said cartridge chamber, said cylinder having its forward end closed, a restricted gas passage from a point in the bore of the barrel immediately forward of the cartridge chamber, through the wall of the barrel into said gas chamber, a tubular piston closed at its rearward end and slidably fitting said cylindrical gas chamber, said piston having an enlarged head externally of said cylinder comprising stop means limiting the forward reciprocation of said piston, the open forward end of said piston when in forwardmost position

being rearwardly of the opening of said gas passage into said cylinder, a slide reciprocable rearwardly to release said breechbolt locking means and having its forward end positioned for engagement and movement by said piston in response to rearward reciprocation thereof following the firing of a cartridge in the cartridge chamber, and stop means restricting rearward reciprocation of said piston to approximately one-half its length, said cylinder having a length substantially twice the length of said piston.
